(57) **CLAIM**

The ornamental design for a candy box, as shown and described.

DESCRIPTION

FIG. 1 is a perspective view of a candy box of the invention.

FIG. 2 is a front view of the candy box of FIG. 1.

FIG. 3 is a rear view of the candy box of FIG. 1.

FIG. 4 is a left view of the candy box of FIG. 1.

FIG. 5 is a right view of the candy box of FIG. 1.

FIG. 6 is a top view of the candy box of FIG. 1.

FIG. 7 is a bottom view of the candy box of FIG. 1.

FIG. 8 is a perspective view of an alternative embodiment of the candy box of FIG. 1.

FIG. 9 is a front view of the candy box of FIG. 8.

FIG. 10 is a rear view of the candy box of FIG. 8.

FIG. 11 is a left view of the candy box of FIG. 8.

FIG. 12 is a right view of the candy box of FIG. 8.

FIG. 13 is a top view of the candy box of FIG. 8; and,

FIG. 14 is a bottom view of the candy box of FIG. 8.

The broken lines in the figures are for illustrative purposes only and are not claimed as part of the design.

1 Claim, 14 Drawing Sheets
